CAM GRINDING MACHINE

Clarence J. Green, Worcester, Mass., assignor to
 Norton Company, Worcester, Mass., a corpora-
 tion of Massachusetts

Application March 31, 1950, Serial No. 153,200

24 Claims. (Cl. 51—101)

1

The invention relates to grinding machines, and more particularly to an automatic cam grinding machine for grinding a plurality of spaced integral cams on a cam shaft to a predetermined contour and taper.

One object of the invention is to provide a simple and thoroughly practical automatic cam grinding machine to grind a plurality of cams which taper in opposite directions. Another object of the invention is to provide an automatic grinding machine in which the cams on one end of the cam shaft may be ground to a predetermined taper in one direction and the remaining cams ground to a predetermined taper in the opposite direction. Another object of the invention is to provide an automatic cam grinding machine in which alternate pairs of cams may be ground to predetermined tapers in opposite directions.

A further object is to provide a wheel slide which is arranged to swivel in a horizontal plane and to provide a fluid motor which is arranged to position the wheel slide when in a central position for a grinding wheel truing operation, or to swivel the wheel slide in either direction to facilitate grinding predetermined tapers in opposite directions on the cams to be ground. Another object of the invention is to provide an automatic control for swiveling the wheel slide which is actuated automatically by the longitudinal movement of the taper to swivel the wheel slide into a central position for a grinding wheel truing operation or in either direction to facilitate grinding cams with surfaces tapered in opposite directions.

In the accompanying drawings in which is shown one of various possible embodiments of the mechanical features of this invention,

Fig. 1 is a front elevation of the improved automatic cam grinding machine;

Fig. 2 is a plan view of the grinding machine;

Fig. 3 is a vertical cross-sectional view, on an enlarged scale, taken approximately on the line 3—3 of Fig. 1, showing the grinding wheel feeding mechanism;

Fig. 4 is a diagrammatic view showing the mechanism for swivelling the wheel slide and the wheel slide base, together with a hydraulic piping and electrical wiring diagram of the controls therefor;

Fig. 5 is a diagrammatic view showing a modification of the mechanism for swivelling the wheel slide and wheel slide base, together with a hydraulic piping and electric wiring diagram of the controls therefor;

2

Fig. 6 is a fragmentary rear elevation, on an enlarged scale, of the swivelling motor and associated parts for swivelling the wheel slide and the wheel slide base;

5 Fig. 7 is a fragmentary plan view, on an enlarged scale, of the swivelling motor and associated parts;

Fig. 8 is a fragmentary plan view, on an enlarged scale, partly in section, of the grinding wheel slide showing the wheel spindle reciprocating mechanism;

10 Fig. 9 is a diagrammatic view showing the relative positions of the grinding wheel, wheel spindle, and pivot for the wheel slide with the wheel in a central or truing position and also swivelled in opposite directions for grinding opposite tapers on the cams being ground;

Fig. 10 is a fragmentary front elevation, on an enlarged scale, showing the gauge plug for locating the grinding wheel laterally relative to the pivot for the wheel slide base;

15 Fig. 11 is a fragmentary side elevation, on an enlarged scale, showing the location of the gauge plug for setting up the grinding wheel relative to the pivot for the wheel slide base; and

Fig. 12 is a diagrammatic view substantially identical to Fig. 5 excepting that it shows a number of additional table dogs.

An automatic cam grinding machine has been illustrated in the drawings comprising a base 10 which supports a longitudinally movable worktable 11 on the usual flatway 12 and V-way 13 formed on the upper surface of the base 10.

The base 10 also supports a transversely movable wheel slide 15 which is arranged to slide transversely on a V-way 16 and a flatway 17 formed on the upper surface of a wheel slide base 18. The wheel slide 15 is provided with a rotatable wheel spindle 19 which supports a rotatable grinding wheel 20. The grinding wheel 20 may be driven by means of an electric motor 21 which is mounted on the upper surface of the wheel slide 15. The motor 21 is connected by a V-belt drive (not shown) contained within a guard 22 (Figs. 1 and 2).

The worktable 11 serves as a support for a pivotally mounted rock bar 25 which is pivotally supported in bearing brackets (not shown) fixedly mounted on the upper surface of the table 11. The rock bar 25 serves as a support for a master cam spindle 26 which extends within a headstock housing 27. The master cam spindle 26 is provided with a cam shaft supported center 28 for supporting the left-hand end of a cam shaft 29 to be ground. The rock bar 25 also sup-

ports a footstock 30 having a footstock center 31 for supporting the right-hand end of the cam shaft 29.

The master cam spindle 26 may be driven by an electric motor 35 mounted on the upper surface of the headstock housing 27. The motor 35 is drivingly connected in a manner (not shown) positively to rotate the master cam spindle 26 and the cam 29 to be ground. The master cam spindle 26 is provided with a plurality of master cams 32 which are arranged to be successively engaged by a master cam roller 33 for controlling the rocking movement of the rock bar 25 so as to generate a predetermined contour on the cam being ground. This mechanism as a part of the present invention may take any suitable form and therefore has not been illustrated in detail. The drive for the master cam spindle 26 and the arrangement of the master cams and follower roller may be identical with that shown in the prior U. S. Patent No. 2,185,837 to G. Crompton, Jr., dated January 2, 1940, to which reference may be had for details of disclosure not contained herein.

A suitable wheel feeding mechanism is provided for feeding the grinding wheel slide 15 transversely relative to the wheel slide base 18. This mechanism is preferably arranged so that the wheel slide may be readily fed toward or from the work piece regardless of the position of the wheel slide base. As illustrated in the drawings a rotatable feed screw 40 is supported in anti-friction bearings 41 and 42 which are in turn fixedly supported within a depending housing 43 projected from the lower surface of the wheel slide base 18. The grinding wheel slide 15 is provided with a depending half nut 44 which projects downwardly from the underside of the wheel slide and meshes with the feed screw 40. The forward end of the feed screw 40 is connected by means of a universal joint 45 with a rotatable sleeve 46. A shaft 47 is slidably keyed within a central aperture within the sleeve 46. The shaft 47 is connected by means of a universal joint 48 with a rotatable shaft 49 journaling in anti-friction bearings 50 and 51 which are fixedly supported relative to the base 18. A gear 52 mounted on the left-hand end of the shaft 49 (Fig. 3) meshes with a gear 53 which is rotated by the manually operable feed wheel 54. It will be readily apparent from the foregoing disclosure that rotation of the feed wheel 54 will be transmitted through the mechanism above described to rotate the feed screw 40 so as to impart a transverse feeding movement of the wheel slide 15 either toward or from the cam shaft 29 being ground. A micrometer wheel feed adjusting mechanism 55 which may be of the standard well known variety such as for example that shown in the expired U. S. patent to C. H. Norton, No. 762,838, dated June 14, 1904, to which reference may be had for details of disclosure not contained herein. This micrometer adjusting mechanism 55 serves to facilitate precisely adjusting a stop abutment (not shown) relative to a pivotally mounted stop pawl 56 which is pivotally mounted on the front of the machine base 10. Due to the universal joints 45 and 48 together with the telescopic shaft 47 within the sleeve 46, a feeding movement may be transmitted to the feed screw regardless of whether the wheel slide base is in a central or truing position or is swiveled in either direction for grinding a tapered surface on the cam being ground.

A suitable mechanism is provided for travers-

ing the worktable 11 longitudinally relative to the base for positioning successive cams on the cam shaft 29 in operative relationship with the grinding wheel 20 for a grinding operation. This mechanism may comprise a manually operable traverse wheel 60 which is mounted on the outer end of a rotatable shaft 61. The inner end of the shaft 61 is provided with a gear (not shown) which meshes with a rack bar 62 mounted on the underside of the table 11. It will be readily apparent from the foregoing disclosure that rotation of the traverse wheel 60 will move the table 11 longitudinally in either direction depending upon the direction of rotation of the handwheel 60.

In order to operate the machine automatically the table 11 may be moved longitudinally by means of a hydraulic mechanism comprising a cylinder 63 which contains a slidably mounted piston 64. The piston 64 is connected to the left-hand end of a piston rod 65 (Fig. 4). The right-hand end of the piston rod 65 is connected to a bracket 66 which is fixedly mounted on the worktable 11. It will be readily apparent that as fluid under pressure is passed through a pipe 67 into a cylinder chamber 68, the piston 64 together with table 11 will be moved toward the right. During this movement, fluid within a cylinder chamber 69 may exhaust through a pipe 70. Similarly as fluid under pressure is admitted through the pipe 70 into the cylinder chamber 69, the piston 64 together with the table 11 will be moved toward the left.

A suitable automatic control mechanism for controlling the admission of fluid to the cylinder 63 may be provided for automatically indexing the table successively to position cams on the cam shaft 29 into operative relationship with the grinding wheel 20. This mechanism as a part of the present invention may take any suitable form, and consequently has not been illustrated in detail. This mechanism may be substantially identical with that shown in the prior U. S. Patent No. 2,185,837, above referred to, to which reference may be had for details of disclosure not contained herein.

A grinding wheel truing tool or diamond 75 (Fig. 4) is adjustably mounted on the rock bar 25 and is arranged so that when the table 11 is traversed to an extreme left-hand end position beyond the last cam on the right-hand end of the cam shaft 29, the diamond or truing tool 75 will be passed across the peripheral face of the grinding wheel 20 to true the same.

In the grinding of automotive cam shafts in accordance with the present practice in many automotive shops, it is desirable to not only provide a cam having a predetermined contour but also tapering from side to side so that when installed in the automotive engine, rotation of the cam on the valve tappet will cause a rotary motion to be imparted to the tappet. In some automotive engine designs it is necessary due to the arrangement of valves and tappets to provide cams having peripheral surfaces tapering in opposite directions. In some cases it is desirable to provide a taper toward the left on all of the cams on the left-hand end of the cam shaft 29, as shown in Fig. 4, and to provide a taper toward the right on the remainder of the cams on the right-hand end of the shaft 29. In order to accomplish this desired result a swivelling mechanism, such as for example a hydraulically operated mechanism is provided for swivelling the wheel slide base in a horizontal plane from a cen-

tral or truing position in one direction to produce the required taper on part of the cams on the shaft 29 after which the wheel slide base is swiveled into the opposite extreme position for producing a predetermined taper on the remainder of the cams in an opposite direction. This mechanism may comprise a hydraulic cylinder 80 which is fixedly mounted on the base 10. The cylinder 80 contains a slidably mounted piston 81 (Figs. 4 and 6). The piston 81 is connected to one end of a piston rod 82. The other end of the piston rod 82 passes through a clearance hole 83 in a bracket 84 which is fixedly mounted on the underside of the wheel slide base 18. The piston rod 82 is held in a fixed position relative to the bracket 84 by means of a nut 85 screw threaded on the left-hand end of the piston rod 82. The wheel slide base 18 is connected by means of a vertically arranged stud 86 with the base 10. As shown in Figs. 2 and 4 axis of the pivot stud 86 is located directly under the center of the grinding wheel 20 in a vertical plane midway between the side faces of the grinding wheel and normal to the axis of the wheel spindle, so as to facilitate swivelling the wheel slide base 18 a predetermined amount in either direction to facilitate grinding tapers of the same degree in opposite directions on predetermined cams on the cam shaft 29 regardless of the diameter of the grinding wheel. It will be readily apparent that when fluid under pressure is passed through a pipe 87 into a cylinder chamber 88, at the right-hand end of the cylinder 80, the piston 81 will be moved toward the left (Fig. 4) to swivel the wheel slide base 18 and the wheel slide 15 in a counter-clockwise direction into the position illustrated in Fig. 4. During this movement fluid within a cylinder chamber 89 at the left-hand end of the cylinder 80 may exhaust through a pipe 90.

Similarly when fluid under pressure is admitted into the pipe 90 into the cylinder chamber 89, the piston 81 will be moved toward the right (Fig. 4) to swivel the wheel slide base 18 and the grinding wheel slide 15 in a clockwise direction into the dotted line position 18a as shown in Fig. 4. This swivelling movement of the wheel slide base 18 and the grinding wheel 15 serves to position the grinding wheel 20 for grinding a predetermined taper toward the right on the cams located on the right-hand half of the cam shaft 29.

It is desirable to provide means for truing a true cylindrical surface on the periphery of the grinding wheel. This is preferably accomplished by positioning the wheel slide base 18 and the wheel slide 15 in a central position with the axis of the grinding wheel spindle parallel with the axis of the cam shaft 29 being ground. In order to automatically locate the wheel slide base in a central position a hydraulically operated mechanism is provided comprising a cylinder 95 which contains a slidably mounted piston 96. The piston 96 is provided with an integral piston rod 97 having a tapered end portion 98 which is arranged to mate with a V-shape notch 99 formed in a plate 100 fastened to the rear end of the wheel slide base 18. A compression spring 101 surrounds the piston rod 97 and is interposed between the piston 96 and an end cap 102 at the lower end of the cylinder 95 (Fig. 4). The spring 101 serves normally to maintain the piston 96 in an uppermost position (Fig. 4) so that the tapered portion 98 of the piston rod is in an inoperative position. When it is desired to true

the grinding wheel, fluid under pressure may be admitted into a pipe 103 into the upper end of the cylinder 95 to cause a downward movement of the piston 96. At the same time fluid under pressure is passed through the pipe 90 to swivel the wheel slide base 18 in a clockwise direction. This clockwise swivelling movement of the wheel slide base 18 continues until the tapered end portion 98 engages the notch 99 which serves to lock the wheel slide base 18 and the wheel slide 15 in a central or truing position.

The actual amount of swivel of the wheel slide base 18 and the grinding wheel slide 15 is very slight being only sufficient to produce tapered surfaces on the work piece amounting to a fraction of one degree. In the average case the amount of taper used is from five to twenty-five minutes. As shown in the diagram the amount of taper both on the cams being ground and the swivel of the wheel slide base 18 and the wheel slide 15 has been somewhat exaggerated so as to clarify the operation of the machine. A pair of opposed stop screws 104 and 105 (Figs. 6 and 7) are provided for limiting the swivelling movement of the wheel slide base 18 in opposite directions. The stop screws 104 and 105 are screw threaded into lugs 106 and 107 respectively which are fixedly mounted relative to the base 10. Stop stud 108 projects downwardly from the wheel slide base 18 and is arranged in the path of the stop screws 104 and 105. A pair of lock nuts 109 and 110 are provided for locking the stop screws 104 and 105 respectively in adjusted positions.

A suitable hydraulic control mechanism is provided for controlling the admission to and exhaust of fluid from the cylinders 80 and 95. This mechanism may comprise a solenoid actuated control valve 112. This valve is a piston type valve having a valve stem 113. The valve stem 113 is normally held in a right-hand end position, as illustrated in Fig. 4, by means of a compression spring 114 contained within the left-hand end of the valve 112. An electric solenoid 115 is provided for shifting the valve stem 113 in a direction toward the left (Fig. 4). In the position of the valve 112 (Fig. 4) fluid under pressure from a suitable source of supply such as for example a fluid pump (not shown) contained within the grinding machine base 10 forces fluid under pressure through the pipe 116 to the valve 112. In the position of the valve 112 (Fig. 4) fluid under pressure passing through the pipe 116, passes through the valve 112 and out through a pipe 117 to other mechanisms of the machine. In this position of the valve 112 fluid within a cylinder chamber 118 in the cylinder 95 may exhaust through the pipe 103 into the valve 112. The exhaust fluid entering the valve 112 passes through a central aperture 119 and out through an exhaust pipe 120. When the solenoid 115 is energized, the valve stem 113 is moved toward the left so that fluid under pressure in the pipe 116 passes through the valve 112 into the pipe 103, into the valve chamber 118 to cause the piston 96 to move downwardly (Fig. 4), to shift the tapered end 98 of the piston rod 97 into operative engagement with the block 100 so that when the wheel slide base swivels into a central position the tapered portion 98 will drop into the notch 99 to locate the wheel slide base 18 and the grinding wheel slide 15 in a central position for a grinding wheel truing operation with the axis of the grinding wheel spindle arranged parallel with the table 11 and cam shaft 29.

A fluid pressure actuated control valve 125 is provided for controlling the admission to and exhaust of fluid from the swivel motor or cylinder 89. This valve is a piston type valve having a slidably mounted valve member 126 which is shifted longitudinally within the valve casing when fluid under pressure is passed into end chambers 127 or 128. In order to control the movement of the valve piston 126, a solenoid actuated pilot valve 129 is provided comprising a valve stem 130 which is fastened to one end of a slidably mounted valve member 131. A compression spring 132 normally holds the valve member 131 in a right-hand end position (Fig. 4). An electric solenoid 133 is provided which when energized serves to shift the valve member 131 into a left-hand end position. As shown in the drawings fluid under pressure from the source passing through the pipe 116 passes through the pilot valve 129, through a passage 134 into the end chamber 128 to move and hold the valve member 126 in a left-hand end position. In this position of the valve 126 fluid under pressure in the pipe 116 passes through a chamber 135 in the valve member 126 and passes out through the pipe 87 into the cylinder chamber 88 to move the piston 81 toward the left (Fig. 4) into its left-hand end position so as to swivel the wheel slide base 18 and grinding wheel slide 15 in a counter-clockwise direction into position illustrated in Fig. 4. When the solenoid 133 is energized to shift the valve member 131 toward the left, fluid under pressure within the pipe 116 passes through the pilot valve member 131, through a passage 136 into the end chamber 127 to move the valve member 126 toward the right. When the valve member 126 is in its right-hand end position fluid under pressure in the pipe 116 passes through the valve chamber 135 and out through a pipe 137, through cylinder chamber formed at the lower end of the cylinder 95 (Fig. 4). Fluid then passes through the pipe 90 into the cylinder chamber 89 to move the piston 81 toward the right (Fig. 4) which serves to swivel the wheel slide base 18 in a clockwise direction into the dotted line position 18a. This movement serves also to shift the wheel slide 15 also in a clockwise direction so as to position the grinding wheel 20 for grinding a taper in the opposite direction on the cams on the right-hand half of the cam shaft 29.

Successive cams on the cam shaft 29 are ground while the table 11 is intermittently indexed longitudinally toward the right (Fig. 4). After the last cam on the left-hand end of the cam shaft 29 has been ground, the table 11 traverses idly in a direction toward the left to return the parts of the machine to the initial position. As the table 11 approaches a left-hand end position, a dog 140 depresses a plunger 141 to close a pair of normally open limit switches LS9 and LS10. The closing of the limit switch LS9 closes a circuit to energize the solenoid 115 to shift the valve stem 113 toward the left so that fluid under pressure in the pipe 116 passes through the valve 112, through the pipe 103 into the cylinder chamber 118 to move the piston 96 downwardly (Fig. 9) so that the tapered end 98 of the piston rod 97 engages the plate 100. At the same time, the closing of the limit switch LS10 serves to energize a relay switch 143 which closes a circuit to energize the solenoid 133. Energizing the solenoid 133 serves to shift the pilot valve stem 130 toward the left so that fluid under pressure in the pipe 116 passes through the pilot valve 129, through the passage 136 into the valve chamber

127 to shift the valve member 126 toward the right. When the valve member 126 reaches its right-hand end position fluid under pressure within the pipe 116 may pass through the valve chamber 135, through the pipe 137 into the cylinder chamber 102. Fluid under pressure entering the cylinder chamber 102 passes through the pipe 90 into the cylinder chamber 89 to cause the piston 81 to move toward the right thus swiveling the wheel slide base 18 and grinding wheel slide 15 in a clockwise direction until the tapered end 98 slides into engagement with the notch 99. The notch 99 serves to locate the wheel slide base 18 and grinding wheel slide 15 in a central or truing position with the wheel spindle 19 arranged parallel to the cam shaft 29 and the table 11. Downward movement of the piston 96, closes the port at the end of the pipe 137 so as to cut-off fluid under pressure from the pipe 90 thereby relieving pressure on the piston 81 during the truing operation while the tapered end 98 of the rod 97 is in engagement with the notch 99. Continued movement of the table 11 toward the left passes the truing tool 75 across the periphery of the grinding wheel 20 after which the table 11 reverses and the tool 75 makes a second pass across the wheel to true a cylindrical face thereon after which the table stops in a loading position. Movement of the table 11 toward the right into a loading position, moves the dog 140 off the plunger 141, the plunger 141 moves upwardly under the influence of the spring 142, so as to open the limit switches LS9 and LS10. The opening of the limit switch LS9 deenergizes the solenoid 115 so that the released compression of the spring 114 shifts the valve member 113 toward the right into the position illustrated in Fig. 4. In this position of the valve 112, fluid within the cylinder chamber 118 may exhaust through the pipe 103, through a central passage in the valve member and exhausts through the pipe 120. The opening of the limit switch LS10 does not effect the solenoid 133, since a holding circuit in the relay switch 143 holds the relay switch closed so that after the pressure has been relieved from the cylinder chamber 118, the release compression of the spring 101 moves the piston 96 upwardly and allows fluid under pressure passing through the pipe 90 to continue the movement of the piston 81 toward the right to impart a further swiveling movement of the wheel slide base 18 and the wheel slide 15 in a clockwise direction to position the wheel slide base in the dotted line position 18a for the start of the next grinding operation.

As shown diagrammatically in Fig. 9, the grinding wheel 20 is shown in a truing position. The swiveling movement of the wheel slide base 18 and grinding wheel slide 15 in a clockwise direction, shifts the wheel spindle 19 and grinding wheel 20 into broken line positions 19b and 20b (Fig. 9). This movement serves to position the grinding wheel for grinding a tapered surface on the cams located on the right-hand end of the cam shaft 29, the surfaces of the cams being tapered in a direction toward the right. When the table 11 has been successively indexed to the central portion of the cam shaft 29, in its movement toward the right, the dog 144 engages and actuates the limit switch LS11 to open the holding circuit of the relay 143 so as to deenergize the switch 143. This actuation of the relay switch 143 deenergizes the solenoid 133 thus releasing the compression of the spring 132 which returns the valve member 131 in a direction toward the right into the position illustrated in Fig. 4. When

the valve member 131 reaches its right-hand end position fluid under pressure may pass into the valve chamber 128 to move the valve member 126 toward the left so that fluid under pressure within in the pipe 116 may pass through the valve chamber 135, through the pipe 87 into the cylinder chamber 88 to move the piston 81 toward the left thus swivelling the wheel slide base 18 and the grinding wheel slide 15 in a counter-clockwise direction into the position illustrated in Fig. 4. The wheel spindle 19 and grinding wheel 20 are thus shifted from positions 19b and 20b (Fig. 9) into positions 19a and 20a so that the grinding wheel 20 will be positioned for grinding a taper in the opposite direction on the remainder of the cams on the cam shaft 29 as the table 11 is intermittently indexed toward the right. It will thus be seen that as shown in Figs. 4 and 9 cams tapering in the opposite direction may be ground on opposite ends of the cam shaft 29.

It may be desirable to grind alternate adjacent pairs of cams on the cam shaft 29 tapering in opposite directions as shown diagrammatically in Fig. 5. In the modification shown in Fig. 5, a pipe 150 serves to supply fluid under pressure to a solenoid actuated valve 151 having a valve stem 152 connected with a valve member 153. A compression spring 154 serves normally to maintain the valve member 153 in a right-hand end position. A solenoid S1 is provided for shifting the valve stem 152 and the valve member 153 toward the left. When the solenoid S1 is energized, fluid under pressure within the pipe 150 may pass through the valve 151 and through a pipe 155 into the cylinder chamber 118 to cause the piston 96 to move downwardly (Fig. 5) so that the piston rod 97 moves into the path of a stop surface 158 formed on the plate 100. During this movement, fluid may exhaust from the valve 151 through a pipe 156.

A fluid actuated control valve 160 is provided for controlling the admission of fluid under pressure to the cylinder 80. The valve 160 is provided with a slidably mounted valve member 161 and end chambers 162 and 163. A pilot valve 164 is provided for controlling the shifting movement of the valve member 161. The pilot valve 164 comprises a valve stem 165 which is fixedly connected to a valve member 166. In the position of the valve 164 (Fig. 5) fluid under pressure in the pipe 150 passes through a passage 167 into the end chamber 163 to shift the valve member 161 toward the left so that fluid under pressure within the pipe 150 may pass through a valve chamber 183, through a pipe 168 into a cylinder chamber 88 to move the piston 81 toward the left thereby causing a counter-clockwise swivelling movement of the wheel slide base 18 and the grinding wheel slide 15 into the position illustrated in Fig. 5. During movement of the valve member 161 toward the left (Fig. 5), fluid within the end chamber 162 may exhaust through a passage 169 and through the pilot valve 164. The valve stem 165 is arranged to be shifted longitudinally by a pair of solenoids S2 and S3. As illustrated in Fig. 5 solenoid S2 is energized to position the valve member 166 in its right-hand end position.

The valve 160 also serves to control the admission of fluid to a fluid actuated control valve 170. The valve 170 comprises a slidably mounted valve member 171 and end chambers 172 and 173. A pilot valve 174 is provided for controlling the shifting movement of the valve member 171. The pilot valve 174 comprises a valve stem 175 which is fastened to a valve member 176. A compression

spring 177 serves normally to hold the valve member 176 in a right-hand end position. A solenoid S4 is provided for shifting the valve stem 175 and the valve member 176 toward the left. In the position shown in Fig. 5, fluid under pressure in the pipe 150 may pass through the pilot valve 174, through a passage 178 into the end chamber 172 to shift the valve member 174 toward the left into the position as illustrated in Fig. 5. During this movement of the valve member 171, fluid within the end chamber 173 may exhaust through a passage 179 and out through the pilot valve 174. A pipe 182 connects the valve 170 with the valve 160. When the valve member 161 is shifted into its right-hand end position, fluid under pressure in the pipe 150 may pass through the valve chamber 183, through the pipe 182 into the valve chamber 181 in the valve 170. In the position of the valve 170 as shown in Fig. 5, fluid under pressure entering the valve chamber 181 may pass through the pipe 180 into the cylinder chamber 88 to cause the piston 81 to move toward the right. When the valve member 171 is moved into the right-hand end position by energization of the solenoid S4, fluid under pressure within the valve chamber 181 may pass through the pipe 184 into the cylinder chamber 102 formed at the lower end of the cylinder 95 so as to cause an upward movement of the piston 96 to move the piston rod 97 upwardly into an inoperative position.

To facilitate automatically controlling the valves 151, 160 and 170, a plurality of limit switches actuated by dogs adjustably mounted on the front edge of the table 11 are provided. An adjustable table dog 190 is provided for actuating a vertically movable plunger 191 against the compression of a spring 192. A downward movement of the plunger 191 as caused by the dog 190 serves to close the normally open limit switches LS9 and LS10. A normally open limit switch 195 is arranged to be actuated by a pair of spaced adjustable dogs 196 and 197 when the table is moved toward the right. A normally open limit switch 198 is arranged to be closed by an adjustable dog 199 when the table 11 is moved toward the right. Similarly a normally open limit switch 200 is arranged to be actuated by an adjustable dog 201 when the table 11 is moved toward the right.

The operation of the modified construction shown in Fig. 5 is somewhat similar to that shown in Fig. 4 except that the wheel slide 15 and wheel slide base 18 are swivelled after each pair of cams have been ground so that tapered surfaces tapering in the opposite direction are produced on adjacent pairs of cams. The table dogs 196, 197, 199 and 201 are arranged so that during the movement of the table 11 toward the left the dogs ride idly over the respective limit switches. As shown in Fig. 5 the table 11 indexes toward the right to grind the last cam on the left-hand end of the cam shaft 29 after which the grinding wheel slide retreats and the table 11 moves through an idle stroke toward the left. As the grinding wheel 20 approaches the truing tool 75, the dog 190 engages and depresses the plunger 191 to close the limit switches LS9 and LS10. The closing of the limit switch LS9 serves to energize the solenoid S1 to shift the valve 151 so that fluid under pressure from the pipe 150 passes through the valve 151 and through the pipe 155 into the cylinder chamber 118 to cause a downward movement of the piston 96 thereby moving

11

the piston rod 97 into the path of a stop surface 158 formed on the plate 100. At the same time closing of the limit switch LS10 energizes the solenoid S3 to shift the valve member 166 toward the left thereby shifting the valve member 161 toward the right so that fluid under pressure from the pipe 150 passes through the valve chamber 183, through the pipe 182 into the valve chamber 181 of the valve 170. Fluid under pressure entering the valve chamber 181 passes out through the pipe 180 into the cylinder chamber 89 to cause the piston 81 to move toward the right thereby swivelling the wheel slide base 18 and wheel slide 15 in a clockwise direction until the stop surface 158 engages the piston rod 97 to position the wheel slide base 18 and wheel slide 15 in a central position to move the grinding wheel 20 in the full line position (Fig. 9) for a truing operation. The continued movement of the table 11 toward the left passes the diamond or truing tool 75 across the face of the grinding wheel 20 to true a cylindrical surface thereon. During this movement the wheel spindle 19 is arranged parallel with the cam shaft 29 and the table 11. After one complete reciprocation of the truing tool across the face of the grinding wheel, the machine stops and the ground cam shaft may be removed from the machine and replaced with a new cam shaft to be ground.

In this position, the table 11 has moved a sufficient distance toward the left so that the dog 201 is at the left of the limit switch 200. When the next grinding cycle is started the table starts moving toward the right to position the first cam in an operative position relative to the grinding wheel 20. During this positioning movement, the dog 201 closes the limit switch 200 to energize the solenoid S4 thereby shifting the pilot valve 174 to move the valve member 171 toward the right so that fluid under pressure will pass from the valve chamber 181 through the pipe 184 into a cylinder chamber 102 at the lower end of the cylinder 95 to move the piston 96 upwardly into the position illustrated in Fig. 5 with the piston rod 97 out of the path of the stop surface 158 of the plate 100. The pressure is still passing through the pipe 180 into the cylinder chamber 89, so that as soon as the piston rod 97 withdraws from engagement with the stop surface 158, the pressure within the cylinder chamber 89 will cause a further clockwise swivelling of the wheel slide base 18 and grinding wheel slide 15 to position the grinding wheel 20 in position 20b (Fig. 9) for grinding the first pair of cams on the cam shaft 29. After the first two cams on the right-hand end of the cam shaft have been ground and the table 11 starts the next indexing movement toward the right, the dog 197 engages and closes the limit switch 195 to energize the solenoid S2 thereby shifting the pilot valve 164 into the position illustrated in Fig. 5 so that fluid under pressure entering the valve chamber 183 will pass through the pipe 188 into the cylinder chamber 88 to move the piston 81 toward the left thereby causing a counter-clockwise swivelling of the wheel slide base 18 and grinding wheel slide 15 to position the grinding wheel 20 in position 20a (Fig. 9) while grinding the third and fourth cams on the cam shaft 29. After the third and fourth cams have been ground and the table 11 starts its indexing movement toward the right, the dog 199 engages and closes the limit switch 198 which serves to energize the solenoid S3 to shift the pilot valve 164 toward the left and the valve

10

member 161 toward the right so that fluid under pressure within the valve chamber 183 will pass through the pipe 182 into the valve chamber 181 of the valve 170 and through the pipe 180 into the cylinder chamber 89 so as to move the piston 81 toward the right thereby swivelling the wheel slide base 18 and grinding wheel slide 15 in a clockwise direction to position the grinding wheel 20 in position 20b (Fig. 9) while grinding the fifth and sixth cams on the cam shaft 29. During the next indexing movement of the table toward the right, the dog 196 engages and closes the limit switch 195 so as to again energize the solenoid S2 and thereby to cause a swivelling movement of the wheel slide base 18 and wheel slide 15 to position the grinding wheel 20 in position 20a (Fig. 9) while grinding the seventh and eighth cams on the cam shaft.

The above described modification facilitates grinding tapers on successive pairs of cams tapering in the opposite direction. By the provision of additional table dogs, if desired, the grinding wheel may be readily swivelled after each cam has been ground to tapered surfaces which taper in opposite directions, such additional dogs are shown in Fig. 12, being indicated by the reference characters 196a, 196b, 199a, and 199b.

It is desirable to provide a wheel spindle reciprocating mechanism for reciprocating the grinding wheel spindle 19 axially within its bearings during a grinding operation. This mechanism may comprise a worm 210 (Fig. 8) mounted on the wheel spindle 19. The worm 210 meshes with a worm gear 211 mounted on a vertical shaft 212. The vertical shaft 212 is provided at its upper end with an eccentric stud 213 which supports an eccentric disc 214. The eccentric disc 214 is surrounded by one part of a connecting rod 215. The connecting rod is preferably made in two parts to facilitate adjustment as will be hereinafter described. An adjustable part 216 of the connecting rod 215 is provided with a yoked end 217 which engages a stud 220 carried by a pivotally mounted yoked member 218. The yoked member 218 is pivotally mounted on a stud 219 which is fixed relative to the wheel slide 15. A tension spring 221 is connected between a stud 222 on the yoked member 218 and a stud 223 fixedly mounted within the wheel slide 15. The spring 221 serves normally to maintain the stud 220 positioned within the yoke 217. It will be readily apparent from the foregoing disclosure that rotation of the wheel spindle 19 will be imparted through the worm 210, the worm gear 211, the shaft 212, the eccentric stud 213, the eccentric disc 214 to oscillate the connecting rod 215 which serves to impart an oscillating movement to the yoked member 218 thereby reciprocating the wheel spindle 19 axially within its bearings. The yoked member 218 is provided with opposed studs (not shown) which engage a groove (not shown) formed on the wheel spindle 19.

As above explained, the pivot 86 for the wheel slide base 18 is located with its axis in a central plane of the grinding wheel, normal to the axis of the grinding wheel spindle in order to facilitate swivelling the wheel slide base 18 and grinding wheel slide 15 in either direction to grind oppositely tapered surfaces on the cams being ground. When the grinding wheel reciprocating mechanism is employed for a grinding operation, it is desirable that the reciprocation which may be of the order of $\frac{1}{2}$ to $\frac{1}{4}$ of

an inch, be arranged so that the grinding wheel 20 reciprocates an equal amount in opposite directions relative to the axis of the pivot stud 86. In order to accomplish this result, an adjustment is provided to vary the length of the connecting rod 215. The adjustable part of the connecting rod 216 is provided with an elongated slot 224. A clamping screw 225 passes through the slot 224 and is screw threaded into the connecting rod 215. In order to facilitate precise adjustment of the connecting rod part 216, a pull-screw 226 passes through a clearance hole in the part 216 and is screw threaded into the connecting rod 215. A push-screw 227 is screw threaded through a portion of the part 216 and bears against a portion of the piston rod 215. It will be readily apparent from the foregoing disclosure that by loosening the clamping screw 225 and manipulating the adjusting screws 226 and 227, the effective length of the piston rod 215—216 may be varied if desired.

In order to facilitate setting up the wheel spindle reciprocating mechanism and thereby locating the grinding wheel relative to the pivotal axis of the stud 86, a gauge plug 230 is mounted on the wheel slide base 18. The gauge plug 230 is located directly below a portion of the grinding wheel 20, so that by means of measuring instruments the grinding wheel may be centered relative to the plug 230 which also centers the wheel relative to the pivotal axis of the pivot stud 86. In order to set up the reciprocating mechanism so that the reciprocatory stroke of the grinding wheel is centered relative to the axis of the pivot stud 86. The eccentric stud 213 and the eccentric disc 214 are positioned in a mean position as illustrated in Fig. 8. While the eccentrics are positioned in this position, the length of the connecting rod 215—216 is adjusted by manipulation of the clamping screw 225 and the adjusting screws 226 and 227 so that the grinding wheel 20 will be centered laterally relative to the gauge plug 230. After this adjustment has been made, the clamping screw 225 may be again tightened to lock the part 216 in adjusted position relative to the connecting rod 215. It will be readily apparent from the foregoing disclosure that adjustment of the length of the connecting rod 215—216 serves to adjust the position of the yoke 218 and thereby to adjust the position of the wheel spindle 19 axially within its bearings. With the adjustment made in the above mentioned position of the parts, a reciprocatory stroke of the grinding wheel will be obtained which will be precisely centered relative to the axis of the pivot stud 86 so that equal tapers in the opposite direction may be produced on successive cams on the cam shaft 29.

The operation of the improved automatic cam grinding machine will be readily apparent from the foregoing disclosure. The machine stops in a loading position with the table 11 positioned so that the grinding wheel 20 is opposite the right-hand end of the cam shaft 29. The cycle of operation of the machine may be substantially identical to that disclosed in the prior Patent No. 2,185,837 to G. Crompton, Jr., dated January 2, 1940, above referred to. When the grinding cycle is started the table 11 starts movement toward the right to shift the first cam on the right-hand end of the cam shaft 29 in an operative position for grinding. During this shifting movement of the table, the wheel slide base

18 and the grinding wheel slide 15 are swiveled in a clockwise direction to position the grinding wheel for grinding a predetermined tapered surface on the cam. After the first cam has been ground the table 11 is again indexed and successive cams are ground to the desired and predetermined taper. As shown in Fig. 4 the machine is arranged for grinding the cams on the right-hand end of the shaft tapering toward the right. After all of these cams have been ground, on the next table indexing movement the swivelling mechanism is actuated to shift the wheel slide base 18 and grinding wheel slide 15 in a counter-clockwise direction into position 20a (Fig. 9) for grinding the remaining cams on the cam shaft. In the modification shown in Fig. 5 the swivelling of the wheel slide base 18 and grinding wheel slide 15 takes place after each pair of cams have been ground so that alternate pairs of cams are ground with faces tapering in opposite directions. After all of the cams on the cam shaft have been ground, the table 11 may be traversed through an idle stroke toward the left. As the truing tool 75 approaches the grinding wheel, the wheel slide base swivelling mechanism operates to swivel the wheel slide base 18 and grinding wheel slide 15 to a central or truing position to locate the wheel spindle 19 parallel with the longitudinal movement of the table 11 for a grinding wheel truing operation. After the table traverses the diamond across the face of the grinding wheel and returns, the table 11 stops in a loading position after which the ground shaft may be removed from the machine and a new shaft to be ground inserted there instead.

It will thus be seen that there has been provided by this invention apparatus in which the various objects hereinabove set forth together with many thoroughly practical advantages are successfully achieved. As many possible embodiments may be made of the above invention and as many changes might be made in the embodiments above set forth, it is to be understood that all matter hereinbefore set forth or shown in the accompanying drawings is to be interpreted as illustrative and not in a limiting sense.

I claim:

1. In a grinding machine having a transversely movable wheel head, a rotatable grinding wheel thereon, a pivotal mounting for the head, means to feed said head transversely, a longitudinally movable work table having a rotatable work support thereon, means for moving the table longitudinally successively to position spaced portions of a work piece relative to the grinding wheel, a fluid motor to swivel said head in either direction, and means including a control valve mechanism actuated by and in timed relation with said table movement to control the swivel motor so as to swivel said head in one direction to facilitate grinding a predetermined taper in one direction on part of the portions to be ground and to swivel said head in the opposite direction to facilitate grinding a predetermined taper in the opposite direction on the remainder of the portions to be ground.
2. In a grinding machine, as claimed in claim 1, in combination with the parts and features therein specified of means including a slidably mounted locating pawl to facilitate positioning the wheel head in a central position for a truing operation, and means including a piston and cylinder for actuating said pawl.

3. In a grinding machine, as claimed in claim 1, in combination with the parts and features therein specified of means including a slidably mounted locating pawl to facilitate positioning said head in a central position for a truing operation, a piston and cylinder to actuate said pawl, a control valve for said piston and cylinder, and means including adjustable dogs on the table for actuating said control valves automatically to control the swivelling movement of the wheel head in either direction and to locate the wheel head in a central position in timed relation with the longitudinal movement of the table.

4. In a cam grinding machine having a base, a transversely movable wheel head, a rotatable grinding wheel thereon, a pivotal mounting for the head, means to feed said head transversely, a longitudinally movable table, a rotatable cam shaft support thereon, means for moving the table longitudinally successively to position spaced cams in operative relation to the grinding wheel, a piston and cylinder to swivel said head in either direction, adjustable stops to limit the swivelling movement of the head in either direction, and means including a control valve mechanism actuated by and in timed relation with the table movement to control the piston and cylinder so as to alternately swivel said head in opposite directions after each cam has been ground to facilitate grinding a predetermined taper in opposite directions on alternate cams to be ground.

5. In a cam grinding machine having a base, a transversely movable wheel head, a rotatable grinding wheel thereon, a pivotal mounting for the head, means to feed said head transversely, a longitudinally movable table, a rotatable cam shaft support thereon, means for moving the table longitudinally successively to position spaced cams in operative relation to the grinding wheel, a piston and cylinder to swivel said head in either direction, adjustable stops to limit the swivelling movement of the head in either direction, and means including a control valve mechanism actuated by and in timed relation with the table movement to control the piston and cylinder so as to alternately swivel said head in opposite directions after each pair of cams has been ground to facilitate grinding a predetermined taper in opposite directions on alternate pairs of cams to be ground.

6. In a cam grinding machine having a base, a transversely movable wheel head, a rotatable grinding wheel thereon, a pivotal mount for said wheel head, means to feed said head transversely, a longitudinally movable work table having a rotatable cam shaft support thereon, means for moving the table longitudinally successively to position successive cams in operative relation with the grinding wheel, a fluid motor to swivel said head in either direction, adjustable stops to limit the swivelling movement of the head in either direction, and means including a control valve mechanism automatically actuated by and in timed relation with the longitudinal movement of the table to control the swivel motor so as to swivel the head in one direction to facilitate grinding a predetermined taper in one direction on a portion of the cams to be ground and to swivel said head in the opposite direction to facilitate grinding a predetermined taper in the opposite direction on the remainder of the cams to be ground.

7. In a grinding machine having a transversely movable wheel head, a swivelling support for said

wheel head, a fluid motor to swivel said head, means including a control valve for controlling said fluid motor so as to swivel the head in either direction for grinding tapers in opposite directions on a work piece, and means including a locating pawl for locating the wheel head in a central position for a grinding wheel truing operation.

8. In a grinding machine having a base, a transversely movable wheel head having a rotatable grinding wheel thereon, a pivotal mounting for the wheel head, a longitudinally movable table having a rotatable work support thereon, means for moving the table longitudinally to position a work piece relative to the grinding wheel, a fluid motor to swivel said head in either direction to facilitate grinding tapers in opposite directions on spaced portions of the work piece, means including an index pawl to facilitate locating the wheel head in a central position for a truing operation, and means including a piston and cylinder actuated by and in timed relation with the longitudinal movement of the table to control the movement of said pawl.

9. In a grinding machine having a base, a transversely movable wheel head, a rotatable grinding wheel thereon, a pivotal mounting for the wheel head, means to feed said head transversely, a longitudinally movable work table having a rotatable work support thereon, means for moving the table longitudinally successively to position spaced portions on a work piece relative to the grinding wheel, a fluid motor to swivel said head in either direction, adjustable stops to limit the swivelling movement of the head in either direction, means including a solenoid-actuated control valve for controlling said swivel motor, a plurality of table dogs adjustably mounted on said table, and means including a switch actuated thereby for controlling said valve automatically to swivel said head in timed relation with the table movement.

10. In a grinding machine having a base, a transversely movable wheel head, a rotatable grinding wheel thereon, a pivotal mounting for the wheel head, means to feed said head transversely, a longitudinally movable work table having a rotatable work support thereon, means for moving the table longitudinally successively to position spaced portions on a work piece relative to the grinding wheel, a fluid motor to swivel said head in either direction for a taper grinding operation, adjustable stops to limit the swivelling movement of the head in either direction, means including a solenoid-actuated control valve for controlling the fluid motor, means including an index pawl to facilitate locating the wheel head in a central position for a truing operation, a fluid motor to actuate said pawl, means including a solenoid-actuated control valve therefor, a plurality of adjustable dogs on said table, and a plurality of limit switches actuated by said dogs to actuate the control valves in timed relation with the longitudinal movement of said table.

11. In a grinding machine having a wheel slide base, a wheel slide thereon, a swivel for said wheel slide base, means including a fluid motor to swivel said slide base, a rotatable wheel spindle on said slide to support a grinding wheel, a spindle reciprocating mechanism including a yoked member to reciprocate said spindle axially, means including a connecting rod to oscillate said yoke, and means to adjust the length of said rod to facilitate positioning the reciprocating

stroke of the grinding wheel so that it is centered relative to the pivotal axis of said swivel.

12. In a grinding machine having a transversely movable wheel head, a rotatable grinding wheel thereon, a pivotal mounting for the head, means to feed said head transversely, a longitudinally movable work table having a rotatable work support thereon, means for moving the table longitudinally successively to position spaced portions of a work piece relative to the grinding wheel, means to swivel said head in either direction, and means actuated by and in timed relation with said table movement to control the swivel means so as to swivel said head in one direction to facilitate grinding a predetermined taper in one direction on part of the portions to be ground and to swivel said head in the opposite direction to facilitate grinding a predetermined taper in the opposite direction on the remainder of the portions to be ground.

13. In a cam grinding machine having a base, a transversely movable wheel head, a rotatable grinding wheel thereon, a vertically arranged pivotal mounting for the head, means to feed said head transversely, a longitudinally movable table, a rotatable cam shaft support thereon, means for moving the table longitudinally successively to position spaced cams in operative relation to the grinding wheel, means to swivel said head in either direction, adjustable stops to limit the swivelling movement of the head in either direction, and means actuated by and in timed relation with the table movement to control the swivelling means so as to alternately swivel said head in opposite directions after each cam has been ground to facilitate grinding a predetermined taper in opposite directions on alternate cams to be ground.

14. In a cam grinding machine having a base, a transversely movable wheel head, a rotatable grinding wheel thereon, a pivotal mounting for the head, means to feed said head transversely, a longitudinally movable table, a rotatable cam shaft support thereon, means for moving the table longitudinally successively to position spaced cams in operative relation to the grinding wheel, means to swivel said head in either direction, adjustable stops to limit the swivelling movement of the head in either direction, and means actuated by and in timed relation with the table movement to control the swivelling means so as to alternately swivel said head in opposite directions after each pair of cams has been ground to facilitate grinding a predetermined taper in opposite directions on alternate pairs of cams to be ground.

15. In a cam grinding machine having a base, a transversely movable wheel head, a rotatable grinding wheel thereon, a pivotal mount for said wheel head, means to feed said head transversely, a longitudinally movable work table having a rotatable cam shaft support thereon, means for moving the table longitudinally successively to position successive cams in operative relation with the grinding wheel, means to swivel said head in either direction, adjustable stops to limit the swivelling movement of the head in either direction, and means automatically actuated by and in timed relation with the longitudinal movement of the table to control the swivel means so as to swivel the head in one direction to facilitate grinding a predetermined taper in one direction on a portion of the cams to be ground and to swivel said head in the opposite direction to facilitate grinding a predetermined

taper in the opposite direction on the remainder of the cams to be ground.

16. In a grinding machine having a transversely movable wheel head, a swivelling support for said wheel head, means to swivel said head in opposite directions, means including adjustable stops for limiting the swiveling movement of the head in either direction for grinding tapers in opposite directions on a work piece, and means including a locating pawl for locating the wheel head in a central position for a grinding wheel truing operation.

17. In a grinding machine having a base, a transversely movable wheel head having a rotatable grinding wheel thereon, a pivotal mounting for the wheel head, a longitudinally movable table having a rotatable work support thereon, means for moving the table longitudinally to position a work piece relative to the grinding wheel, means to swivel said head in either direction to facilitate grinding tapers in opposite directions on spaced portions of the work piece, means including an index pawl to facilitate locating the wheel head in a central position for a truing operation, and means actuated by and in timed relation with the longitudinal movement of the table to control the movement of said pawl.

18. In a cam grinding machine having a base, a transversely movable wheel head, a rotatable grinding wheel mounted thereon, a pivotal mounting for the wheel head mounted on the base for swivelling movement about a vertical axis, a longitudinally movable table, a rotatable cam shaft support thereon, means for moving the table longitudinally successively to position spaced cams in operative relation to the grinding wheel, means to swivel said head in either direction, adjustable stops to limit the swivelling movement of the head in either direction, and means actuated by and in timed relation with the table movement to control the swivelling means so as to alternately swivel said head in opposite directions after each cam has been ground to facilitate grinding a predetermined taper in opposite directions on alternate cams to be ground.

19. In a grinding machine having a base provided with a movable support that has means for rotatably supporting a cam shaft to be ground and provided with a movable support carrying a rotatable peripherally operative grinding wheel having means for axially reciprocating said grinding wheel, means mounting and guiding said supports on said base for relative movement in a direction longitudinally of the axis of said cam shaft supporting means and for relative movement therebetween in a direction transverse of said axis and including means providing a vertical pivot for said grinding wheel support for swiveling it in opposite directions about a vertical axis to provide respectively opposite angularities between the line along which said grinding wheel reciprocates and the axis of said cam shaft supporting means for grinding opposite tapers, the mid-plane between the side faces of the grinding wheel when the latter is at the mid-point of its stroke of reciprocation and said vertical pivoting axis falling in the same vertical plane, means for effecting said first-mentioned relative movement in successive stages to successive grinding stations for positioning spaced cam-shaft cams and said grinding wheel in operative relation, means to swivel said vertically pivoted support in either direction about said vertical axis to provide either of said opposite

angularities, and means including spaced control elements and coacting actuatable control means between which relative movement takes place in timed relation with said relative longitudinal movement between said two supports in said successive stages, for controlling said swiveling means to swivel said pivoted support in one direction to grind a taper on a cam at one station and to swivel said support in opposite direction to grind a taper in opposite direction on a cam at another station.

20. A cam grinding machine as claimed in claim 19 in which said means for axially reciprocating said grinding wheel comprises an axially reciprocable grinding wheel driving spindle with a yoked member to reciprocate said spindle axially with driving means to oscillate said yoked member and including means of adjustable length to facilitate positioning the reciprocatory stroke of the grinding wheel so that its mid-point coincides with said vertical plane that includes said vertical pivoting axis.

21. In a cam grinding machine having a base provided with a movable support carrying a rotatable grinding wheel and provided with a movable support that has means for rotatably supporting a cam shaft to be ground, means mounting and guiding said supports on said base for relative movement therebetween in a direction longitudinally of the axis of said cam shaft supporting means and for relative movement therebetween in a direction transverse of said axis and including means providing a vertical pivot for one of said supports for swiveling it in opposite directions about a vertical axis to provide respectively opposite angularities between the face of the grinding wheel and the axis of said rotatable cam shaft supporting means for grinding opposite tapers, means for effecting said first-mentioned relative movement in successive stages to successive grinding stations for individually positioning spaced cam-shaft cams and said grinding wheel in operative relation, means to swivel said vertically pivoted support in either direction about said vertical axis, and means including spaced control elements and coacting actuatable control means between which relative movement takes place in timed relation with said relative longitudinal movement in successive stages between said two supports, for controlling said swiveling means to swivel said pivoted support in one direction to grind a taper on a cam at one station and to swivel said support in opposite direction to grind a taper in opposite direction on a cam at another station.

22. A cam grinding machine as claimed in claim 21 in which the means to swivel said vertically pivoted support comprises a reversible fluid motor and said spaced control elements and coacting actuatable control means therefor comprise respectively a notched plate movable with one of said supports and a plunger-like index

pawl coacting therewith whereby the stroke of movement of said index pawl is controlled by said notched plate, and valve means for affecting the supply of fluid to said fluid motor and including valve means responsive to the position of said index pawl relative to said notched plate.

5 23. A cam grinding machine as claimed in claim 21 in which the means to swivel said vertically pivoted support comprises reversible motor means and said spaced control elements and coacting actuatable control means therefor comprise respectively a notched plate movable with one of said supports and a plunger-like index pawl coacting therewith whereby the stroke of movement of said index pawl is controlled by said notched plate, said plunger-like index pawl having means operable in one direction upon the index pawl bottoming in said notched plate and operating in reverse direction upon said index pawl moving out of said notched plate for affecting the operation of said motor means.

10 24. In a cam grinding machine, a base having longitudinal and transverse guideways one of which is formed in a member that is movably supported on said base for limited shifting movement in reversible direction about a vertical axis thereby to change the angularity between said two guideways in either direction from a true 90-degree angular relationship therebetween, a table guided for longitudinal movement in said longitudinal guideways and having a rotatable cam shaft support thereon, a support movable along said transverse guideway and rotatably supporting a grinding wheel, means for moving the table longitudinally along said longitudinal guideway to successive grinding stations to position spaced cams of a cam shaft carried by said rotatable support in operative relation to the grinding wheel, and motor means for moving said guideway member in either direction about said vertical axis and including control means therefor coacting with means that move with said table, for shifting said guideway member in one direction to grind a taper on a cam at one station and to shift said guideway member in opposite direction to grind a taper in opposite direction on a cam at another station.
